(57) **CLAIM**

The ornamental design for a power tool, as shown and described.

DESCRIPTION

FIG. 1 is a bottom, rear, and right side perspective view of a power tool showing our new design;

FIG. 2 is a bottom, rear, and left side perspective view thereof;

FIG. 3 is a bottom, front, and right side perspective view thereof;

FIG. 4 is a bottom, front, and left side perspective view thereof;

FIG. 5 is a bottom plan view thereof; and,

FIG. 6 is a rear elevation view thereof.

The portions of the power tool shown in broken lines are included for the purpose of illustrating environment and form no part of the claimed design. The portions of the power tool shown in broken lines having unequal length segments illustrate the boundary of the claimed design and form no part of the claimed design.

1 Claim, 6 Drawing Sheets
